UNITED STATES PATENT OFFICE.

TORQUATO TASSO FISCHER, OF NEW YORK, N. Y.

DESIGN FOR A PIANO-PEDAL SUPPORT.

SPECIFICATION forming part of Design No. 30,065, dated January 24, 1899.

Application filed December 5, 1898. Serial No. 698,375. Term of patent 3½ years.

To all whom it may concern:

Be it known that I, TORQUATO TASSO FISCHER, a citizen of the United States, residing at New York, county of New York, 5 State of New York, have invented and produced a certain new and original Design for a Piano-Pedal Support, of which the following is a full, clear, and exact description.

My invention relates to a new and original 10 design for a piano-pedal support and is shown in the accompanying drawings, in which—

Figure 1 is a front elevation. Fig. 2 is a plan view.

A is a base, the summit of which is dished 15 or recessed, suggesting to the eye a space of a substantially U-shaped outline.

The leading feature of my design comprises a unitary U-shaped member having upwardly-directed arms integral therewith and

at opposite sides thereof, giving to this member, as a single article, a U-shaped appearance. On the inner sides of the two opposite arms of this U-shaped member are inwardly-directed projections B B, appearing in a plane substantially opposite one another when 25 viewed from in front and from above. On the outside of one of said arms appears an outward projection C, also substantially in the plane of the previously-referred-to 30 projections.

What I claim is—

The design for a piano-pedal support substantially as herein shown and described.

TORQUATO TASSO FISCHER.
